DISTRIBUTING DEVICE FOR DOUGHNUT MACHINES

Alexander S. T. Lagaard, Minneapolis, Minn.

Application April 29, 1933, Serial No. 668,507

25 Claims. (Cl. 53—7)

My invention relates to doughnut machines and particularly to the type of doughnut machine in which the doughnuts are caused to travel abreast in columns along a receptacle containing a cooking liquid.

An object of the invention resides in providing a doughnut machine of such nature in which a doughnut former is employed adapted to discharge at a fixed locality and in further providing means for delivering the doughnuts from the doughnut former to the various columns along which the doughnuts travel in the receptacle.

Another object of the invention resides in constructing the doughnut machine with an elongated receptacle and in providing a longitudinal conveyor for progressing the doughnuts in column formation along said receptacle and in further providing a transverse conveyor for delivering the doughnuts from the doughnut former to the various columns.

A feature of the invention resides in providing two longitudinal conveyors having a turnover device disposed therebetween and in intermittently operating said longitudinal conveyors simultaneously.

An object of the invention resides in operating said doughnut former and transverse conveyor during the cessation of operation of said longitudinal conveyors.

Another object of the invention resides in operating said turnover device simultaneously with the operation of said doughnut former and the transverse conveyor.

A still further object of the invention resides in alternately operating said doughnut former and transverse conveyor and in repeating the operation thereof a number of times equal to the number of columns of doughnuts progressed along said receptacle, said formation and delivery of doughnuts all occurring during cessation of movement of the longitudinal conveyor.

An object of the invention resides in providing a constantly driven shaft and in providing intermittent mechanism driven by said shaft for intermittently operating said longitudinal conveyors simultaneously.

A still further object of the invention resides in providing intermittent mechanism for operating said turnover device from said constantly driven shaft during the cessation of operation of said longitudinal conveyor.

Another object of the invention resides in providing a counter shaft and intermittently operating said counter shaft from said constantly

driven shaft, said counter shaft being operated during the cessation of movement of said longitudinal conveyor.

A still further object of the invention resides in providing an auxiliary shaft and in rotating said shaft at a rate of speed equal to the number of columns of doughnuts times the speed of said counter shaft.

A feature of the invention resides in alternately operating said transverse conveyor and doughnut former from said auxiliary shaft.

Other objects of the invention reside in the novel combination and arrangement of parts and in the details of construction hereinafter illustrated and/or described.

In the drawings:

Fig. 1 is a side elevational view of a doughnut machine illustrating an embodiment of my invention.

Fig. 2 is a plan view of a portion of the machine shown in Fig. 1 with parts thereof illustrated in section.

Fig. 3 is a fragmentary elevational sectional view taken on line 3—3 of Fig. 2.

Fig. 4 is a fragmentary sectional view taken on line 4—4 of Fig. 2.

Fig. 5 is a view similar to Fig. 4 taken on line 5—5 of Fig. 2.

Fig. 6 is a plan sectional view of a portion of the invention situated at the turnover device.

Fig. 7 is an elevational sectional view taken on line 7—7 of Fig. 6.

Fig. 8 is an elevational sectional view taken on line 8—8 of Fig. 6.

Fig. 9 is an elevational sectional view taken on line 9—9 of Fig. 2.

In the cooking of doughnuts in a machine employing a longitudinally traveling conveyor in which the doughnuts are arranged abreast, considerable difficulty has been encountered in machines having a plurality of doughnut formers in that it is practically impossible to cause all of the doughnut formers to deliver doughnuts of the same size and shape. Where a traveling doughnut former has been utilized adapted to deliver at different localities with respect to the longitudinal conveyor, it has further been found extremely inconvenient due to the fact that only a small receptacle for dough could be utilized and great difficulty was encountered in filling this receptacle during the operation of the machine.

In addition distortion of the doughnuts occurred through movement of the receptacle. The present invention provides a machine by means of which all these disadvantages are eliminated.

My invention, which is best shown in Fig. 1, consists of a framework 10 which carries an elongated receptacle 11 for the reception of a cooking liquid which may be heated in any desired manner, and along which the doughnuts are progressed during the cooking thereof. At the forward end of the machine is provided a longitudinally extending conveyor 12 and at the rearward end of the machine is another longitudinal conveyor 13 by means of which the doughnuts are progressed along the receptacle 11. Between these conveyors is disposed a turnover device 14 (Fig. 7) which causes the doughnuts to be inverted to procure uniform cooking on both sides thereof. At the forward end of the doughnut machine is provided a doughnut former 15 which is adapted to discharge the doughnuts into the receptacle 11. A transverse conveyor 16, Fig. 2, delivers the doughnuts from the doughnut former 15 to positions from which the same may be picked up by the conveyor 12 and progressed through the receptacle 11. The transmission device indicated in its entirety at 17 serves to intermittently operate the two conveyors 12 and 13 simultaneously and to alternately therewith operate the turnover device 14. Another transmission mechanism indicated in its entirety at 18 serves during the cessation of operation of the conveyors 12 and 13 to operate the doughnut former 15 and the conveyor 16 alternately and to operate the same a number of times equal to the number of columns of doughnuts progressed through the machine. These various parts will now be described in detail.

The frame 10 consists of two longitudinal frame members 19 and 20 which are supported on a number of posts 21, 22, 23, 24, and 25. The frame members 19 and 20 may be constructed as angles and are arranged with the flanges 26 and 27 extending downwardly and outwardly as best shown in Fig. 3. The posts 21 are disposed inwardly of the flanges 26 and are riveted or welded thereto. The posts 23, 24 and 25 are secured to the outer surfaces of the flanges 26 and are similarly attached thereto. For transverse spacing of the longitudinal frame members 19 and 20, three transverse frame members 28, 29 and 30 are employed of which the frame members 28 are attached to flanges 19 and 20 at the rear ends thereof and of which the frame members 29 and 30 are secured to the transverse flanges of the posts 21 and 22. These frame members are dropped considerably below the longitudinal frame members 19 and 20 and serve a purpose to be presently described in detail. In addition to these frame members two other transverse frame members 36 and 37 are employed which are attached to the posts 21 and 25 near the lower ends thereof.

The posts 21, 22, 23, 24, and 25 are reinforced through tie rods 31 which may consist of angles secured to the inner surfaces of the longitudinally extending flanges of these posts and riveted thereto. Suitable braces 32 and 33 secured to the longitudinal frame members 19 and 20 and to posts 21 and 25 brace the entire frame structure longitudinally. Similar braces 34 and 35 secured to the posts 21 and 25 and to the transverse frame members 36 and 37 brace the frame structure transversely.

The receptacle 11 is in the nature of a shallow pan or tank constructed with a bottom 38 and sides 39 and 40. This receptacle provides an elongated way along which the doughnuts are

progressed and during the travel of which the doughnuts are cooked through the agency of the cooking liquid contained within the receptacle. The receptacle 11 is of such dimensions as to occupy the space between the two longitudinal frame members 19 and 20 and is supported through a number of clip angles 41 which are riveted to the sides 39 and 40 of said receptacle and which rest upon the flanges 27 of said longitudinal frame members. These clip angles may be bolted to the said flanges of the said longitudinal frame members if desired through bolts 42, best shown in Fig. 2. The receptacle 11 is formed at the rear with an end indicated in dotted lines at 43 in Fig. 1 which inclines from the bottom 38 up to the upper edges of the two sides 39 and 40. The front of the receptacle 11 is constructed with a depressed portion 44 best shown in Figs. 2 and 9 in which the transverse conveyor 16 is disposed. This depressed portion is constructed with transverse walls 45 and 46 and end walls 47 and 48. The transverse wall 45 is offset at 49 to provide a chamber 50 within the receptacle in which transmission mechanism for driving the conveyor 16 may be disposed. The receptacle 11 is further formed with an end wall 51 at the extreme forward portion thereof.

Conveyor 12 is best shown in Figs. 1, 2, and 7. This conveyor consists of two endless chains 52 and 53 which pass over sprockets 54 and 55 secured to two transverse shafts 56 and 57. The shaft 57 is journaled in bearings 58 attached to the upper ends of the posts 22. These bearings are formed with slots 59 through which bolts 60 extend whereby the said bearings may be slid along the upper portion of the receptacle 11 to procure tightening of the chains 12. The shaft 56 is journaled in a bearing formed in the transmission 17 and is further journaled in another bearing similar to the bearings 58 but not shown in the drawings. For the purpose of propelling the doughnuts through the cooking liquid, a number of blades 260 are employed which are attached to the chains 52 and 53 and which issue outwardly therefrom. These blades are formed with flanges 61 which lie in the plane of the runs of said chain and which are secured to certain links of the chain in any suitable manner. The distance between the blades 260 is somewhat greater than the diameter of the doughnuts so that the doughnuts may be freely received therebetween and progressed. The width of the receptacle 11 and the corresponding width of the blade 260 is equal to or slightly greater than a whole number of doughnuts. In the particular machine shown, the receptacle and conveyor are of a width sufficient to propel four doughnuts abreast along the receptacle 11.

Conveyor 13 is constructed in identically the same manner as conveyor 12, being provided with chains 62 which pass over sprockets 63 and 64. The sprockets 63 are mounted on a shaft 65 journaled in the transmission device 17 and in another bearing similar to that used for shaft 56. The sprockets 64 are attached to a shaft 66 which is journaled in bearing 67 attached to the outer ends of the longitudinally extending frame members 10. These bearings are adjustable along said frame members so that the slack in the chain may be taken up as wear occurs. Attached to the chains 62 are a number of blades 68 similar to the blades 260, which blades are provided with flanges 69 secured to certain of the links of the chain proper. By means of the two chains 12 and 13 the doughnuts may be

progressed from one end of the receptacle 11 to the other.

The various chains 52, 53, and 62 ride upon rails 250. These rails consist of angles secured 5 to the sides 39 and 40 of pan 11 and which extend inwardly into the tank and support the chains at the proper elevation. Guards 25 secured to these rails extend downwardly into the cooking liquid and prevent the doughnuts from 10 passing under said rails.

The two shafts 56 and 65 of conveyors 12 and 13 are spaced from one another to provide room 15 for the turnover device 14 which is disposed between the same. This turnover device consists of a square shaft 169 which is provided at its ends with trunnions 70 adapted to be journaled in bearings 11. Bearings 11 are disposed upon the interior of the receptacle 11 and are attached to the sides 39 and 40 through rivets 72. The 20 shaft 69 has attached to it two blades 73 and 74 which are so disposed as to operate between the blades 68 and 260 of the two conveyors 12 and 13 and to receive the doughnuts discharged by the blades 260, turn them over and deliver 25 them to the blades 68 of conveyor 13. The bottom 38 of the receptacle 11 is depressed as designated at 75 to provide space for the operation of the blades 73 and 74 as the shaft 69 rotates.

At the bottom of the receptacle 38 is provided 30 a number of electrical heating elements 76 by means of which the cooking liquid in the receptacle 11 may be maintained at the proper temperature. These heating elements are diagrammatically illustrated and it can readily be comprehended that any suitable construction such 35 as is now in common use for this purpose may be employed. Also extraneous heat, as from gas flame may be utilized to maintain the proper temperature or any other suitable heating means 40 employed.

For the purpose of procuring discharge of the doughnuts from the receptacle 11 the upwardly inclined rear end 43 of said receptacle is utilized. At such locality the lower run 77 of conveyor 13 45 is caused to incline in parallel relation with respect to the end wall 43. This is accomplished by utilizing two idler sprockets 78 which are mounted on a shaft 79 journaled in bearings 80 which are secured to the upper flange 27 of the 50 two longitudinal frame members 19 and 20. The sprockets 78 bear against the lowermost run of the said conveyor. In conjunction therewith the bearings 67 are somewhat elevated to cause the blades 68 on said conveyor to follow closely to 55 said end wall. As the doughnuts reach the said end wall the blades 68 cause the same to climb the end wall and to be discharged from the rear end of the machine.

In the operation of the two conveyors 12 and 60 13 and the turnover device 14, the two conveyors are simultaneously operated. These conveyors are operated intermittently with respect to the turnover device 14. When the conveyors 12 and 13 function the turnover device 14 is disposed 65 with the blades 73 and 74 thereof arranged as shown in dotted lines in Fig. 7. When the two conveyors 12 and 13 come to rest the blades thereof become disposed as shown in full lines in Fig. 7. During such period the turnover device 14 operates to receive the doughnuts discharged by conveyor 12 and to turn the same over and to deliver the doughnuts to a position whereby the same may be engaged by the blades 68 of conveyor 13. For the purpose of procuring 70 75 the alternate periodic movement of these parts

the transmission device 17 previously referred to is employed. This device is best shown in Figs. 6 and 8 and comprises a gear case 81. The gear case 81 has a back 82, ends 83 and 84, a top 85 and a bottom 86, being open at the front thereof. The bottom 86 rests directly upon the flange 21 of frame member 19 and is provided with feet 88 and 89 also resting upon said flange. Bolts 90 passing through said feet and the flange 21 of frame member 19 serve to hold the case 81 10 rigidly attached to the said frame member. The open forward portion of the case 81 is adapted to be closed through a cover plate 91 which is bolted to a flange 92 formed on the ends 83 and 84 and the top 85 and bottom 86 of said case. 15 This is accomplished through cap screws 93 which pass through said cover plate and are screwed into the flange 92.

As previously stated, the two shafts 65 and 56 which carry the sprockets 63 and 64 of conveyors 20 12 and 13 extend into the gear case 81. These shafts are journaled in bearings 94 and 95 formed on the rear wall 82 of said case. For the purpose of operating the various parts a constantly driven shaft 96 is employed which extends longitudinally 25 of the case 81 and which is journaled in two bearings 97 and 98 formed in the end walls 84 and 83. This shaft lies in the plane of the two shafts 65 and 56.

Simultaneous operation of the two conveyors 30 12 and 13 is accomplished within the gear case 81. For this purpose a sprocket 99 is employed which is attached to the inner end of the shaft 56. Another sprocket 100 of the same size as sprocket 99 is likewise secured to the inner end of the shaft 35 65. A chain 101 passes over these two sprockets. It can readily be comprehended that as the shaft 56 is driven by means to be presently described in detail, that both of the conveyors 12 and 13 are simultaneously operated and at the same rate of 40 speed.

The shaft 56 of conveyor 12 is driven from the shaft 96 through intermittent mechanism which will now be described in detail. In the plane of the two shafts 56 and 65 is provided a boss 102 which is formed on the wall 82 of case 81 and extends inwardly into the interior of case 81. This boss has rigidly mounted in it a stub shaft 103. This shaft has rotatably mounted on it a pinion 104, being a part of a Geneva movement for operating 50 the shaft 56. The pinion 104 meshes with a gear 105 integral with the sprocket 99 previously referred to and another part of said Geneva movement. The gear 104 has an integral bevel gear 106 which meshes with another bevel gear 107 fast 55 on the shaft 96. Gear 104 is held rotatably mounted upon stub shaft 103 by means of a head 108 formed on the end of said shaft. The shaft 96 travels in the direction of the arrow and causes movement of pinion 104 through the two beveled gears 106 and 107. Pinion 104 is constructed with gear teeth 109 which are adapted to mesh with gear teeth 110 on the gear 105. Pinion 104 is further formed with a cylindrical portion 111 60 adapted to successively mesh with arcuate portions 112 and 113 and 114 on the gear 105 situated between the various gear teeth 110 of said gear. By means of this construction it can readily be comprehended that every time the shaft 96 65 is rotated one revolution that pinion 104 makes a corresponding revolution. During the period that the cylindrical part 111 of this pinion engages the arcuate portion 112 of gear 105, gear 105 remains stationary. When the teeth 109 engage teeth 110, 70 75

gear 105 is rotated. The pinion 104 is so designed that gear 105 is stationary for approximately two-thirds of a revolution of shaft 96 and is itself rotated one-third of a revolution when the teeth 109 engage the teeth 110. The diameter of the sprockets 54 and 63 of the two conveyors 12 and 13 is such that one-third of a revolution of shafts 56 and 65 will progress the two conveyors 12 and 13 a distance equal to the distance between the various blades 260 and 68 on said conveyors. In this manner one revolution of shaft 96 procures movement of the two conveyors 12 and 13 equal to the distance between said blades so that the blades always come to rest at the same positions which are indicated in Fig. 7 when the Geneva movement causes locking of the gear 105 and cessation of movement of said conveyors.

For the purpose of operating the turnover device 14 a short shaft 115 is employed which is journaled in a bearing 116 issuing inwardly from the wall 82 of case 81. This shaft is disposed between the two runs of the chain 101 and extends through the case 82 having secured to it upon its outer end a sprocket wheel 117. A chain 118 passes over this sprocket wheel and over another sprocket wheel 119 fast on shaft 169 on which the turnover device is mounted. As shaft 115 is rotated the turnover device is also rotated.

Shaft 115 is driven from shaft 96 as follows: On the extreme end of shaft 65 of conveyor 13 is rotatably mounted a pinion 120 of another Geneva movement. This pinion meshes with a gear 121 of said Geneva movement fast on the shaft 115. A bevel pinion 122 is integral with pinion 120 and meshes with a bevel pinion 123 fast on shaft 96. Pinion 120 is quite like the pinion 104 and the gear 121 is quite similar to the gear 105 excepting that the latter gear is formed with two arcuate portions 124 and 125 instead of three as is the case with gear 105. Inasmuch as the shaft 96 has but two blades 73 and 74 on it the shaft 115 is given but two turns for each revolution of the shaft 96. The teeth on the pinion 120 and the gear 121 are so arranged that the turnover device 14 operates when the two conveyors 12 and 13 are motionless and so that the said turnover device is without motion when the two conveyors 12 and 13 are operating. The stationary position of the turnover device is shown in dotted lines in Fig. 7, while the position of said turnover device in which the same is beginning to turn over the doughnuts I have shown in full lines in this figure.

The transverse conveyor 16 previously referred to is best shown in Figs. 2 and 9. This conveyor consists of two chains 126 and 127. These chains have attached to each of the links thereof, slats 129 which forms a continuous belt covering the entire surface of the conveyor. At suitable intervals are provided blades 130 which extend upwardly from certain of the slats 129, which blades are spaced apart the same distance as the blades 260 and 68 of the conveyors 12 and 13. The two chains 126 and 127 pass over sprockets 131 and 132 which are attached to a shaft 133 disposed within the chamber 50 of the receptacle 11. This shaft is journaled in two bearings 134 and 135 which are secured to the sides 45 and 46 of the portion of the receptacle 11 in which the transverse conveyor is mounted. Bearings 134 and 135 are closed at their ends so that the cooking liquid is prevented from leaking through the same and out of the receptacle 11. Similar sprockets, shafts and bearings are provided at the other ends

of the conveyor 16 by means of which the same is further supported.

The conveyor 16 is disposed immediately below the conveyor 12 at the forward end thereof and is so arranged that the blades 130 of said transverse conveyor just clear the flanges 61 of the conveyor 12. To permit the operation of conveyor 12 during cessation of movement of conveyor 16 the blades 260 are provided with vertical slots 136 which are of such width to receive the said blades 130 as the conveyor 12 is operated.

The doughnut former 15 previously referred to may be of any suitable construction such as now are known in the art. A doughnut former of the type shown in Patent No. 1,747,503 to C. E. Carpenter has been illustrated. The mechanism thereof forming no particular feature of the invention has hence not been shown in this application. The doughnut former 15 consists of a receptacle 137 open at the top and into which the dough is placed. This receptacle is formed with a hopper bottom 138 and terminates in a nozzle 139. The receptacle 137 is attached to a portion 140 of post 21 which extends upwardly above the horizontal frame member 19. For this purpose two bands 142 and 143 are employed which encircle the said receptacle 137 and are formed with nuts 144 by means of which the said bands may be secured to the outwardly extending flange 145 of portion 140 of post 21 through bolts 146. The doughnut former 15 further includes a cut off head 147 which is mounted on the end of a vertically reciprocable spindle 148. Said former further includes a piston, not shown, mounted on a sleeve 149 in which the spindle 148 is vertically slidable. Both these parts are arranged for vertical sliding movement as disclosed in said patent or in any other suitable manner. The upper end of the spindle 148 is provided with a collar 150 by means of which the same may be reciprocated and sleeve 149 is constructed with a similar collar 151 serving a like purpose. The nozzle 139 is so situated that the same deposits doughnuts at the locality indicated in dotted lines at 152, in Fig. 2. The lower edge 153 of nozzle 139 is just above the level of the cooking liquid in the receptacle 11 which prevents splashing of the liquid as the formed doughnuts are discharged into the same. The nozzle 139 is situated medially between the position of two of the blades 130 which are procured when the conveyor 16 comes to rest.

For the purpose of operating the doughnut former 15 and the transverse conveyor 16, the transmission device 18 is employed. This mechanism will now be described in detail.

The transmission mechanism 18 comprises a case 154 having a rear wall 155, a top 156, a bottom 157 and ends 158 and 159, said case being open at the forward portion thereof. For closing this portion of the case, a cover 160 is employed which is adapted to be secured to a flange 161 extending perimetricaly about the various walls of the case. Cap screws 162 passing through the cover 160 are threaded into this flange. The bottom 157 of the case 154 is bolted to the flange 27 of frame member 19 by means of bolts 163 which pass through said flange and which are threaded into bosses 164 formed upon the interior of the bottom 157. A leg 165 issuing outwardly from the wall 159 of said case also has bolts 166 extending therethrough which pass through the flange 27 of frame member 19 in the same manner as the bolts 163. The case 154 is braced through a diagonal brace 167 which is bolted 75

through bolts 168 and 169 to the bottom 168 and to the post 21. By means of this construction case 154 is rigidly supported with respect to the framework of the doughnut machine.

Within the case 154 is rotatably mounted a drive shaft 170. This drive shaft is journaled in bearings 171 and 172 formed in the end walls 159 and 158 of the case proper. Shaft 170 has attached to it a worm gear 173 which meshes with a worm 174 (Fig. 4) fast on a shaft 175. Shaft 175 extends transversely of the shaft 170 and is journaled in bearings 176 and 177 formed in the bottom 157 of case 154. This shaft projects outwardly of the case and has attached to it a pulley 178. A belt 179 passes over the pulley 178 and over a pulley 180 of a motor 181 resting upon the floor of the building in which the machine is disposed. The shaft 170 serves to operate the shaft 96 previously referred to. For this purpose two couplings 182 and 183 are employed which are attached to the shafts 170 and 96 respectively. These couplings have further attached to them a floating shaft 184 by means of which a drive is afforded between shafts 170 and 96. Within the case 154 is rotatably mounted a counter shaft 185. This counter shaft is journaled in bearings 186 and 187 formed on the end walls 159 and 158 of case 154. Upon this shaft is rotatably mounted a gear 188 of a Geneva movement, the pinion 189 of which is mounted on the drive shaft 170. The pinion 189 is provided with teeth 190 and a cylindrical portion 191 similar to the parts of the Geneva movement previously described. The gear 188 is constructed with teeth 192 adapted to mesh with the teeth 190 and with an arcuate portion 193 adapted to be engaged by the cylindrical portion 191 of the pinion 189. Shaft 170 travels in unison with the shaft 185 and one revolution of the said shaft 170 procures one revolution of shaft 185. The teeth 190 extends over half of the circumference of the gear 188 so that shaft 185 is caused to rotate for a period somewhat greater than half the period of rotation of shaft 170 and to remain idle for the remaining portion of the rotation of said shaft. Integral with the gear 188 is a spur gear 194 which meshes with a pinion 195 best shown in Figs. 3 and 9. This pinion is fast on an auxiliary shaft 196 which shaft is journaled in two bearings 197 and 198 formed in the case 154.

The ratio of the gears 195 and 194 is one to four so that four doughnuts are delivered to the longitudinal conveyor by the cross conveyor whenever one cycle of movement of the various parts of the invention are completed.

For operating the transverse conveyor 16, shaft 185 is utilized. This shaft has mounted upon the end of it a sprocket 199. A similar sprocket 200 is secured to the shaft 133. A chain 201 passes over these two sprockets. Conveyor 16 and the sprockets 199 and 200 are so designed that one revolution of shaft 185 procures a movement of said conveyor equal to the distance between the blades 130 thereof. Whenever shaft 185 comes to rest, these blades are in a position to be received within the slots 136 of blades 260 of conveyor 12.

The shaft 185 is driven from the shaft 196 as follows: This is accomplished through a Geneva movement illustrated in detail in Fig. 5. Fast on the shaft 196 is a pinion 202 which is part of the said Geneva movement and which is provided with teeth 203 and a cylindrical portion 204. This pinion meshes with a gear 205 fast on shaft 185. Gear 205 is provided with teeth

206 and a single arcuate portion 207 adapted to engage the cylindrical portion 204 of the Geneva movement. During rotation of the shaft 196 the shaft 185 is caused to alternately rotate and remain stationary.

The doughnut former 15 is operated from two cams 208 and 209 attached to a sleeve 210 rotatably mounted on shaft 185. The sleeve 210 has attached to it a gear 211 forming part of another Geneva movement. A pinion 212 also 10 part of this Geneva movement is mounted on the shaft 196 and may be constructed integral with the pinion 195. This Geneva movement operates to rotate the sleeve 210 intermittently, one revolution of said sleeve for a corresponding 15 revolution of the shaft 196. The Geneva movements operating the shaft 185 and the sleeve 210 are so timed that the conveyor 16 and the doughnut former 15 are operated alternately.

Operating in conjunction with the two cams 208 and 209 are two push rods 213 and 214. These push rods are slidably mounted in guides 215 and 216 which are detachably secured to the case 154 in any suitable manner. The rods 213 and 214 extend upwardly above said case and are 25 further slidably mounted in guides 217 and 218 formed on a bracket 219. Bracket 219 is bolted to the upper end of the portion 140 of post 21 through bolts 220. On the rods 213 and 214 are rigidly secured collars 221. Compression coil 30 springs 222 encircle the said rods and are seated against the undersides of the guides 217 and 218 and against the collars 221 and serve to urge the two rods downwardly and in contact with the two cams 208 and 209. On a standard 223 35 issuing upwardly from the bracket 219 are mounted for oscillation two swinging levers 224 and 225. Pins 226 and 227 pass through these levers and are secured to the standard 223 and serve as fulcrums on which the said levers oscillate. The lever 224 is connected through a fork 228 with the collar 150 while the lever 225 is connected through a fork 229 with the collar 151. Links 230 and 231 pivoted to the ends of the rods 213 and 214 are also pivoted to the ends 232 40 and 233 of the levers 224 and 225 and serve to move said levers vertically and in opposite directions to the movement of said rods as the same are reciprocated through the two cams 208 and 209. By means of the particular construction 50 shown, the piston and head 147 of the doughnut former are so operated as to successively extrude formed parcels of dough which are periodically discharged into the cooking liquid in the receptacle 11.

The operation of my invention is as follows: Assuming the conveyors 12 and 13 to be stationary, gear 104 is engaging the arcuate portion 112 of gear 105 and shafts 56 and 65 are stationary. During such disposition of parts, gear teeth 90 60 of gear 189 are engaged with gear teeth 192 and gear unit 188-194 is being rotated. Through the action of gears 194 and 195, shaft 196 is being rotated. This shaft is rotated four times for each rotation of gear unit 188-194. 65 During each of these rotations, sleeve 210 and shaft 185 are alternately rotated in full revolution. Rotation of sleeve 210 causes the alternate operation of the two push rods 213 and 214 and the formation and ejection of a doughnut from 70 the nozzle 139 of doughnut former 15. The discharge of doughnuts occurs between two of the blades 130 of conveyor 16. The doughnut is discharged into the grease in close proximity to the surface thereof and gently sinks into the grease 75

until it rests on the slats 129 of conveyor 16. As soon as the movement of sleeve 210 terminates, shaft 185 is rotated. This causes the conveyor 16 to be progressed through the action of chain 201 and sprockets 199 and 200, causing the said conveyor to travel a distance equal to the distance between the various blades 130. During such movement, the doughnut is brought into the path of travel of conveyor 12. During the 10 four rotations of shaft 196, four doughnuts are formed, deposited and conveyed, the first doughnut being delivered to the far side of conveyor 12 and the last doughnut to the near side of the conveyor 12. Gear unit 188-194 is then held 15 stationary through the cylindrical part 191 of pinion 189 and the arcuate portion 193 of gear 188. When the conveyor 16 comes to rest, blades 130 are exactly opposite the slots 136 in the blades 60 of conveyor 12. This conveyor is then 20 moved forwardly a distance equal to the distance between blades 60 which removes the doughnuts from the conveyor 15 and progresses the same along the receptacle 11. During the formation and movement of the doughnuts by conveyor 16, the turnover device 14 is being operated which takes the doughnuts from the conveyor 12, turns them over and delivers them to the conveyor 13. In the subsequent operation of the conveyors, the conveyor 13 further progresses 30 the doughnuts through the receptacle 11, the doughnuts being finally discharged from the end of the receptacle through the upwardly inclined run 77 of conveyor 13.

Although I have shown the machine designed 35 to convey four rows of doughnuts abreast, it can be readily comprehended that the machine may be constructed to handle three, five or any other number of columns of doughnuts within reasonable limits.

40 My invention is highly advantageous in that a machine is provided in which doughnuts are positively formed and handled throughout the entire cooking operation thereof. A single doughnut former is used which is stationary and discharged at a single location so that filling of dough in the same and adjustment in manipulation of said former is greatly facilitated. By employing a stationary doughnut former a much larger receptacle may be utilized for dough than 45 would be possible where a movable former was employed. With my invention such doughnut is of exactly the same shape and size so that no variation occurs.

Changes in the specific form of my invention, 50 as herein disclosed, may be made within the scope of what is claimed without departing from the spirit of my invention.

Having described my invention, what I claim as new and desire to protect by Letters Patent is:

60 1. In a doughnut machine, an elongated receptacle for a cooking liquid, a longitudinally extending conveyor adapted to progress the doughnuts in column formation along said receptacle, a doughnut former adapted to discharge at a fixed locality, and a transverse conveyor movable independently of the flow of the cooking liquid for conveying doughnuts from said former to positions adapted to bring the doughnuts into column formation with respect to said longitudinal conveyor.

70 2. In a doughnut machine, means forming a way along which a number of doughnuts may travel abreast, a doughnut former discharging at a fixed locality with respect to said way, and means movable independently of the flow of the

cooking liquid for delivering the doughnuts from said former to adjacent positions within said way.

3. In a doughnut machine, an elongated receptacle for a cooking liquid, a longitudinally extending conveyor for progressing doughnuts in column formation along said receptacle, a doughnut former adapted to discharge at a fixed locality, a transverse conveyor for delivering doughnuts from the doughnut former to various transverse positions with respect to said longitudinal conveyor, means for intermittently operating said longitudinal conveyor, and means for operating said doughnut former and transverse conveyor during cessation of movement of said longitudinal conveyor.

4. In a doughnut machine, an elongated receptacle for a cooking liquid, two longitudinal conveyors arranged end to end, a turnover device between said conveyors, a doughnut former adapted to discharge at a fixed locality, a transverse conveyor for delivering the doughnuts from said former to a position to be conveyed by said conveyors, means for intermittently operating both of said longitudinal conveyors simultaneously, and means for operating said turnover device, doughnut former and transverse conveyor during cessation of movement of said longitudinal conveyors.

5. In a doughnut machine, an elongated receptacle for a cooking liquid, a longitudinal conveyor for progressing doughnuts in column formation along said receptacle, a doughnut former adapted to discharge at a fixed locality, a transverse conveyor for delivering doughnuts from the said longitudinal conveyor, means for intermittently operating said doughnut former and transverse conveyor successively a number of times equal to the number of columns 40 of doughnuts progressed by said conveyor and during cessation of movement of said longitudinal conveyor.

6. In a doughnut machine, means forming a way along which a number of doughnuts may travel abreast, a doughnut former discharging at a fixed locality with respect to said way, and a movable member adapted to direct the doughnuts from said former to the different positions of the doughnuts across said way whereby a successive number of doughnuts may travel abreast along said way.

7. In a doughnut machine, an elongated receptacle for a cooking liquid, a longitudinal conveyor for progressing doughnuts in column formation along said receptacle, a doughnut former adapted to discharge at a fixed locality a transverse conveyor for conveying the doughnuts from said former to different positions transversely 60 with respect to said longitudinal conveyor, a constantly driven drive shaft, means intermittently operated from said drive shaft for propelling said longitudinal conveyor to periodically progress rows of doughnuts along said receptacle, a 65 counter shaft, means for periodically driving said counter shaft from said drive shaft, said operation of said counter shaft alternating with the operation of said conveyor, an auxiliary shaft, means for driving said auxiliary shaft at a rate 70 of speed equal to the number of columns of doughnuts times the rate of speed of said counter shaft, and means intermittently operated by said auxiliary shaft for alternately operating said doughnut former and said transverse conveyor.

8. In a doughnut machine, means forming a way along which a number of doughnuts may travel abreast, a doughnut former discharging at a fixed locality with respect to said way and a transverse conveyor having movable blades for delivering the doughnuts from said former to adjacent positions within said way.
9. In a doughnut machine, an elongated receptacle for a cooking liquid, a conveyor for progressing doughnuts along said receptacle, a turn over device, a driving member, a transmission between said driving member and the turn over device including a set of Geneva gears, a driving mechanism between said driving member and said conveyor including a set of Geneva gears, said gears being arranged to procure alternate operation of said conveyor and turn over device.
10. In a doughnut machine, a receptacle for a cooking liquid, means for progressing doughnuts along said receptacle, a turn over device for turning over the doughnuts in said receptacle, a cutter for depositing doughnuts in said receptacle, a driven member, means for operating said turn over device and progressing means in alternation, and means for operating said doughnut cutter a number of times during cessation of movement of said progressing means.
11. In a doughnut machine, a receptacle for a cooking liquid, means for progressing doughnuts along said receptacle, a turn over device for turning over the doughnuts in said receptacle, a cutter for depositing doughnuts in said receptacle, a driven member, transmission means for driving said turn over device and progressing means from said driven member, a counter shaft geared to said driven member and adapted to operate at a higher rate of speed than said driven member, and means for operating said cutter from said counter shaft.
12. In a doughnut machine, an elongated receptacle for a cooking liquid, a longitudinal conveyor in said receptacle for progressing doughnuts along said receptacle, said receptacle having a depression at the head end of said conveyor, a transverse conveyor disposed within said depression and below the head end of said progressing conveyor, and means for delivering doughnuts to said transverse conveyor.
13. In a doughnut machine, an elongated receptacle for a cooking liquid, a conveyor for progressing doughnuts in a plurality of columns along said receptacle, a second conveyor extending across said receptacle, said second conveyor having blades thereon for moving the doughnuts transversely of the receptacle, blades on said first named conveyor, said blades having openings therein for the reception of the blades on the second conveyor to cause the first conveyor to remove the doughnuts from the second conveyor, and means for operating said conveyors.
14. In a doughnut machine, an elongated receptacle for cooking liquid, a conveyor for progressing doughnuts in a plurality of columns along said receptacle, a second conveyor extending across said receptacle, said second conveyor having blades thereon for moving the doughnuts transversely of the receptacle, blades on said first named conveyor, said blades having openings therein for the reception of the blades on the second conveyor to cause the first conveyor to remove the doughnuts from the second conveyor, said blades on the first conveyor being spaced apart a distance greater than the length
- 5 of the blades on the second conveyor, and means for intermittently operating said conveyors.
15. In a doughnut machine, a receptacle for cooking liquid, means for progressing doughnuts along a plurality of independent courses, a doughnut former adapted to discharge at a fixed locality, and means operating independently of the flow of the cooking liquid for feeding doughnuts from said former to each of said courses.
16. In a doughnut machine, an elongated receptacle for a cooking liquid, conveying means for progressing doughnuts in a plurality of columns along said receptacle, said columns having juxtaposed ends, a doughnut former adapted to discharge at a fixed locality, a traveling blade for conveying doughnuts from said former to each column at the juxtaposed ends of said columns, and means for removing the doughnuts from each of the columns at the other ends thereof.
17. In a doughnut machine, an elongated receptacle for a cooking liquid, conveying means for progressing doughnuts in a plurality of columns along said receptacle, said columns having juxtaposed ends, a doughnut former adapted to discharge at a fixed locality, and a conveyor including a traveling blade for conveying doughnuts from said former to each column at the juxtaposed ends of said column, and means for removing the doughnuts from each of the columns at the other ends thereof.
18. In a doughnut machine, a receptacle for a cooking liquid, means for progressing the doughnuts along two independent courses in the liquid, a doughnut former adapted to discharge at a fixed locality, a movable member for delivering formed doughnuts directly to both courses, and means for removing the doughnuts from both of said courses.
19. In a doughnut machine, a receptacle for a cooking liquid, a longitudinal conveyor for progressing doughnuts in adjacent columns along said receptacle, a transverse conveyor including an endless belt, means for successively depositing formed doughnuts on said belt, means for progressing said transverse conveyor to cause the same to become filled with formed doughnuts and means for periodically operating said longitudinal conveyor when the transverse conveyor is filled to simultaneously transfer all of the doughnuts from said transverse conveyor to the various columns of said longitudinal conveyor.
20. In a machine of the class described, the combination of a frying pan, means adjacent to said pan for forming and delivering doughnuts, a conveyor travelling across the pan and having pockets for receiving the doughnuts formed and delivered as aforesaid and serving to locate the doughnuts in rows extending across the pan, and another conveyor travelling lengthwise of the pan and receiving the rows of doughnuts from the first-mentioned conveyor and transporting them lengthwise of the pan.
21. In a doughnut machine, an elongated receptacle for a cooking liquid, a longitudinal conveyor for progressing doughnuts in column formation along said receptacle, a doughnut former adapted to discharge at a fixed locality, a transverse conveyor for conveying the doughnuts from said former to different positions transversely with respect to said longitudinal conveyor, a constantly driven drive shaft, means intermittently operated from said drive shaft for propelling said

longitudinal conveyor to periodically progress rows of doughnuts along said receptacle, and means intermittently operated from the drive shaft to propel the transverse conveyor during periods of rest of the longitudinal conveyor and at a rate of speed equal to the number of columns of doughnuts times the rate of speed of advancement of the longitudinal conveyor.

22. In a doughnut machine, means forming a way along which a number of doughnuts may travel abreast, a doughnut former discharging at a fixed locality with respect to said way, a movable member adapted to direct the doughnuts from said former to the different positions of the doughnuts across said way, whereby a successive number of doughnuts may travel abreast along said way, and means arresting movement of said member when a doughnut is at its proper position in said way.
23. In a doughnut machine, a receptacle for a cooking liquid, means for progressing the doughnuts along two independent courses in the liquid, a doughnut former adapted to discharge at a fixed locality, a member for directing the travel of the doughnuts from said former to said

courses, said member being movable to direct the doughnuts first to one course and thereafter to the other course.

24. In a doughnut machine, a receptacle for a cooking liquid providing a way along which doughnuts may travel abreast, means for progressing the doughnuts along said way, a doughnut former adapted to discharge at a fixed locality, means for conveying the doughnuts from said doughnut former to said way, means for intermittently operating said first named means, and means for intermittently operating said second named means in alternation with said first named means.

25. In a doughnut machine, a receptacle for a cooking liquid providing a way along which doughnuts may travel abreast, means for progressing the doughnuts along said way, a doughnut former adapted to discharge at a fixed locality, means for conveying the doughnuts from said doughnut former to said way, and means for intermittently operating said second named means.

ALEXANDER S. T. LAGAARD. 25
